ATTORNEYS

UNITED STATES PATENT OFFICE.

JERRY A. PRESCOTT, OF STEELE, NORTH DAKOTA.

DENTAL DISK-HOLDER.

1,018,340.

Specification of Letters Patent. Patented Feb. 20, 1912.

Application filed May 6, 1911. Serial No. 625,609.

To all whom it may concern:

Be it known that I, JERRY A. PRESCOTT, a citizen of the United States, and a resident of Steele, in the county of Kidder and State 5 of North Dakota, have invented a new and Improved Dental Disk-Holder, of which the following is a full, clear, and exact description.

My invention relates to dental disk holders and the object thereof is to provide a simple and inexpensive device whereby in a single structure means may be provided for conveniently holding in accessible position a supply of disks of various sizes.

Reference is to be had to the accompanying drawings forming a part of this specification, in which like characters of reference denote corresponding parts in all the views, and in which—

20 Figure 1 is a perspective view of my device in operative position; Fig. 2 is a vertical sectional view thereof, on the line 2—2 of Fig. 1; Fig. 3 is a perspective view of one of the magazines; Fig. 4 is a similar view 25 showing a modified form of outlet; Fig. 5 is a sectional view of this form.

My device may be conveniently made of two pieces of metal, one portion of which contains the semicylindrical embossings 1, 2, 30 3, 4, 5, 6, together with the offset end portions 7, 8, provided with suitable holes to receive fastening means 9, such as screws or tacks; this forms, in effect, one half of my device. The other half is conveniently 35 formed of another piece of sheet metal having the semicylindrical embossings 10, 11, 12, 13, 14, and 15, which are adapted to be juxtaposed to the portions 1, 2, 3, 4, 5, 6, whereby a series of chambers or magazines 40 are formed, as shown particularly in Fig. 1. The rigidity of the structure is maintained by suitable longitudinally extending portions 16, 17, 18, which lie closely adjacent similar portions provided on one of the 45 pieces of metal and which lie closely adjacent similarly shaped portions on the other piece of metal, this second piece of metal being also provided with offset end portions similar to the end portions 7, 8, and provided with holes which register with the holes in the end portions 7, 8, for the reception of the screws or tacks 9. It will be noted that the diameter of each of these 50 magazines or pockets increases from right to left whereby they may contain a large number of dental disks of various sizes.

The bottom portion of each of these pockets or magazines consists of a pair of forwardly extending fingers 20, 21, preferably integral with one of the pieces of metal from which the pockets are formed, these fingers extending from a down-turned portion 22 carried by this piece of metal, there being a suitable opening 23 between each of the fingers and the lower end portion of each of the embossings 1, 2, 3, 4, 5, 6, being removed for a short distance, as at 24, whereby a disk may be withdrawn from the bottom of any pocket by merely bringing the finger into the opening 23 and drawing the disk forwardly from the bottom of the supply contained therein. It may be desirable in some instances to provide these pockets or magazines with means whereby a pocket of a given diameter may be adapted to contain 75 disks of varying thicknesses and in order to meet such a demand I have provided the construction shown in Figs. 4 and 5. The lower end portion of each of the embossings 1 to 6 inclusive is removed, as at 24', each of 80 these embossings being provided on its front portion and adjacent the lower end thereof, with the threaded stud 30 on which a suitable thumb nut 31 engages. A circular plate 32 is provided with a slot 33 through which 85 the stud 30 passes, the curvature of this plate being the same as that of each of the embossings and the nut 31 being adapted to be tightened, whereby this plate may be held in close contact on each pocket or magazine and at a varying distance from the bottom thereof, whereby its position may be 90 changed in order to admit of the free withdrawal of disks of different thicknesses.

The disks in each of the pockets or magazines are maintained in suitable position therein for easy withdrawal by means of a small weight 40 of substantially the same diameter as the pocket in which it is used. The use of such a weight in keeping the 100 disks closely packed tends to prevent the same from warping or curling while lying within the magazine, the weight being of such a mass that the disks are held in substantially horizontal position and with sufficient pressure against the fingers 20, 21, that when one is desired to be withdrawn the pressure applied thereto in order to withdraw it will not be sufficient to raise the pack of disks upwardly within the pocket. 110

It is obvious that many changes may be made in the form, shape, and size of the

various parts in order to adapt the pockets to disks of different sizes without departing from the spirit of the invention as defined in the following claims.

5 While I have shown six pockets in the drawings as making up my device, it is obvious that it may be made of any number thereof, and it may be desirable to provide a plurality of pockets of the same diameter 10 so that a large number of disks may be held in position for use.

Having thus described my invention, I claim as new, and desire to secure by Letters Patent:—

15 1. A device of the class described comprising two pieces of metal, the intermediate portions of each being provided with a plurality of semi-cylindrical embossings of different widths, the embossed sides of each piece lying adjacent each other with the said embossings in register whereby a series of magazines of varying diameters is secured, one of the said pieces being provided with 20 a plurality of offset fingers extending transversely of each of the magazines at the lower end thereof and spaced from the other piece, a plate having a slot therein, the plate being curved to conform to the curvature of the embossings, a threaded stud carried by each 25 embossing, the stud entering the said slot in the plate and a thumb nut engaging on

the said stud whereby the plate may be adjustably secured in position and adjacent the forward ends of the fingers, thereby permitting disks of varying thicknesses to be successively withdrawn from each magazine. 35

2. A device of the class described, comprising two pieces of metal, the intermediate portions of each being provided with a plurality of semi-cylindrical embossings of different widths, the embossed sides of each piece lying adjacent each other, with the said embossings in register, whereby a series of magazines of varying diameters is secured, the end portions of each of the pieces 40 being offset and secured together, one of the said pieces being provided with a plurality of offset fingers extending transversely of each of the magazines at one end thereof and spaced from the other piece, and a plate 45 movably secured to the other piece, adjacent the forward ends of the fingers, whereby disks of varying thickness may be withdrawn successively from each magazine.

In testimony whereof I have signed my name to this specification in the presence of two subscribing witnesses.

JERRY A. PRESCOTT.
